UNITED STATES PATENT OFFICE

2,007,068

PORTABLE WATER SOFTENER

William C. Beck, Mattoon, Ill.

Application October 28, 1933, Serial No. 695,688

1 Claim. (Cl. 210—24)

This invention relates to water softeners and has for the primary object the provision of a portable device of the above stated character which will efficiently and quickly soften the water taken directly from a hydrant or water output and deliver the softened water to any place desired and is so constructed that the regeneration of the chemical of the softener may be easily and quickly accomplished without soiling or corroding the device and especially the exterior thereof and is equipped with means for preventing the water from forming a channel or single passage through the chemical and which also effectively distributes the incoming water to the chemical.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a side elevation partly in section illustrating a water softener constructed in accordance with the invention.

Figure 2 is a top plan view illustrating the device.

Figure 3 is a plan view of the device with the cover or head removed illustrating the outlet means.

Figure 4 is a detail sectional view illustrating the means of securing the base to the tank or reservoir.

Figure 5 is a plan view illustrating the device with the head or cover removed and showing the screen in position.

Figure 6 is a fragmentary sectional view showing the head with a funnel applied thereto for the purpose of regenerating the chemical of the device.

Figure 7 is a sectional view showing the fitting for securing the intake hose to any type of faucet.

Figure 8 is a fragmentary sectional view illustrating a modified form of connection between the funnel and the head.

Referring in detail to the drawings, the numeral 1 indicates a tank or reservoir of any desired shape and preferably of cylindrical form, as shown in Figure 1, and is supported by a removable base 2. The base has a seat 3 for the lower end of the tank or reservoir and is of the split type equipped with a fastening medium 4 so that the base may be drawn tightly to the tank

or reservoir when the latter is placed within the seat 3. The base is slightly flared to facilitate the supporting of the tank or reservoir and aid in preventing tipping of the latter when in use. The upper end of the tank or reservoir is equipped with a flange 5 apertured to receive bolts or like fasteners 6 for securing to the tank or reservoir a removable head 7 in which is formed a chamber 8. The head is flanged, as shown at 9, to overlie the flange 5 and is apertured to receive the bolts or fasteners 6 and a suitable gasket 10 is positioned between the head and the flange 5 to prevent escape of the contents of the tank or reservoir while the softener is in use. The chamber 8 is in communication with an intake nipple 11 forming an integral part of the head and is designed to connect with a hose coupling 12 of the female type to which an intake hose 13 is connected. The hose at its free end is equipped with a coupling 14 detachably connected to a fitting 15 of substantially L-shape, one branch of which receives a gasket 16 adapted to frictionally grip the discharge end of a faucet 17. The gasket may be forced tightly against the faucet by a set bolt 18 carried by the fitting 15.

The head 7 is provided with a seat 19 surrounding the chamber 8 and in which is positioned a screen 20 overlying the chamber 8 and compelling the incoming water from the faucet to pass therethrough and be effectively distributed into the tank or reservoir over a maximum area of the chemical 21 confined within the tank or reservoir. The tank or reservoir is substantially filled with the chemical 21, as shown in Figure 1 of the drawings.

An outlet port is located in the wall of the tank or reservoir adjacent the upper end of the latter and below the upper surface of the chemical and has secured therein by a packing gland 22 an outlet pipe 23 comprising several sections 40 detachably connected. The outer or discharge end of the outlet pipe 23 is constructed to receive the coupling 24 to which a hose 25 is connected. The innermost section of the outlet pipe 23 is of substantially L-shape with the leg portion 26 in 45 the form of a cylindrical foraminous material 27 which lies in close proximity to the bottom of the tank or reservoir and embedded within the chemical 21. The hose 25 may be of any desired length so that the softened water from the device may be directed to any place desired.

In operation, and when it is desired to obtain softened water, the faucet 17 is opened and the water directly from the hydrant is admitted to the chamber 8 and passes through the screen 20

so that the water will be sprayed over the upper surface of the chemical. The water being under pressure from the hydrant passes from the chemical into the outlet pipe to the hose 25 where it may be directed into any device which may have been elected to receive the softened or treated water.

The top wall of the head 1 is provided with a filling port 27 in which is formed a seat 28 to receive a suitable gasket. The walls of the port above the seat 28 are screw threaded to mesh with the screw threads of a plug 29 which is equipped with a handle 30 to facilitate the removal and application of the plug to the head.

A device of this character after use over a period of time, the chemical employed therein must be regenerated by a suitable solution and to permit this operation to be carried out, the plug 29 is removed and a funnel 31 is threaded into engagement with the seat 28 of the port 27 so that the solution may be easily and conveniently poured or directed into the head and thence through the screen for action on the chemical 21. The funnel 31 is preferably of a size that will receive the full amount of the solution at one time which is necessary to bring about the regeneration of the device.

As shown in Figure 8, the filling port may be surrounded by an upstanding externally screw threaded flange 32 and the funnel used in connection therewith has its discharge neck internally screw threaded to receive the screw threaded flange 32. When the funnel of this character is removed from the head a cap type plug may be employed for closing the filling port.

A device constructed in accordance with the foregoing may be cheaply manufactured and consists of a minimum number of parts and is capable of being easily transported from one place to another and will permit the flow of

water in a reverse direction through the device by simply connecting the hose 13 to the outlet pipe 23. It is desirable at some time to reverse the flow of water for cleansing purposes and the screen 20 will prevent the escape of the chemical 21 during this operation. The regeneration of the chemical can be easily carried out with minimum effort on the part of the operator and without danger of spilling the regenerating solution.

While I have shown and described the preferred embodiment of my invention, it will be understood that minor changes in construction, combination and arrangement of parts may be made without departing from the spirit and scope of my invention, as claimed.

Having described the invention, I claim:

A water softener comprising a chemical container having its upper end open and flanged, a head for the open end of the container and having a chamber and a recess to receive the flanged open end of said container, a screen between the chamber and the container and seated against walls of the recess and the flanged end of said container, said head having a screw threaded port in communication with the chamber and an inlet to admit water to said chamber and through the screen to the container to be distributed over the chemical of the container by said screen, a removable handle type plug for normally closing the port whereby the latter may be opened to receive a funnel for directing a rejuvenating solution into the chamber and thence onto the chemical of the container, and an outlet pipe extending from the lower portion of the container through one side thereof adjacent the flanged end and lying substantially its full length within the chemical of said container.

WILLIAM C. BECK. 40
